United States Patent Office.

EDWIN BENNETT, OF BALTIMORE, MARYLAND, ASSIGNOR TO HIMSELF AND WILLIAM T. GILLENDER, OF PHILADELPHIA, PENNSYLVANIA.

Letters Patent No. 92,568, dated July 13, 1869.

IMPROVED MACHINE FOR CLEANING SAND.

The Schedule referred to in these Letters Patent and making part of the same.

To all whom it may concern:

Be it known that I, EDWIN BENNETT, of the city and county of Baltimore, in the State of Maryland, have invented a new and improved Machine for Cleaning Sand; and I do hereby declare that the following is a full, clear, and exact description thereof, reference being had to the accompanying drawings, making part of this specification, in which—

Figure 1 is a plan view of the machine complete.

Figure 2 is a section taken longitudinally through fig. 1 in a vertical plane, indicated by red line $x\ x$.

Figure 3 is an enlarged sectional view of that part of the machine from which the sand is finally discharged pure.

Similar letters of reference indicate corresponding parts in the several figures.

This invention relates to machinery which is designed for cleansing silicious sand, and preparing it for use in the manufacture of glass, and for other purposes.

To enable others skilled in the art to understand my invention, I will describe its construction and operation.

In the accompanying drawings, A represents a trough, which is supported in a horizontal plane upon sills A' A', and provided inside with a horizontal rotary shaft, B, from which radiates a number of arms or blades, b b, as shown in fig. 1.

At one end of this trough A, a screen, C, is arranged, in an inclined plane, beneath which screen is a pipe, a, through which water is caused to flow into the trough A, across the inflowing stream of sand through the screen C.

The blades or arms b, on shaft B, may be arranged spirally around this shaft, or in any other manner which will cause the sand to be slowly moved to that end of the trough A furthest from the said screen, at which end is a discharge-spout, e, from which the sand, with its impurities, is delivered upon a screen-bottom chute, D.

The screen-bottom chute D is sustained in such manner that it will receive a shaking or vibratory motion from an eccentric, j, which is upon a short shaft carrying a pinion spur-wheel, i.

This wheel i receives motion from a spur-wheel, h, on shaft B, through the medium of spur-wheels h' h'', and shaft B may receive rotary motion from any convenient source.

Directly beneath the screen-portion of the chute D is a trough, E, which may be made of any suitable length, and which is arranged in a horizontal plane, either in a plane parallel to the trough A, or at any desired angle with respect thereto.

If desirable, the trough E may be composed of several sections united, so that it can be shortened when desired.

Within the longest trough, E, is a conveyer, F, com-

posed of several sections of shafts, having screw-threads or feathered blades on their surfaces.

These screw-sections are supported within the trough E by spiders f and short removable coupling-journals s, which latter have prismatic ends, fitted into corresponding sockets formed in the ends of the screw-sections.

The journals s are removable, in order that new ones may be substituted in their places when the old ones wear out, as they will be liable to do, in consequence of the grinding-action of the sand.

Near that end of the trough E furthest from the chute D, and extending transversely across the trough, is a support, d, for a spout, g, which spout is inclined in an opposite direction to the feed of the conveyer, and is intended to direct a current of water toward the chute D, near which is a spout, g', for the escape of water, mixed with impurities washed from the pure sand, from the trough.

Beneath the chute g, the conveyer passes through a tube, G, which may be made of any suitable length, and which enters a chamber, e, in trough E, from which the pure sand is discharged over an inclined plane, e'.

The drawings represent the tube G, cylindrical and closely fitting that portion of the screw-shaft which passes through it; but I do not confine myself to the precise form of this tube, as other equivalent means may be employed for effecting the same result, to wit, the packing of the sand, at or near its point of discharge from trough E, in such manner as to separate it from the body of water in this trough, and deliver the sand comparatively dry.

Operation.

Motion being given to the shaft B, screw-bottom chute D, and conveyer F, the impure sand is delivered into the trough A, through the screen C, which latter separates lumps, stones, sticks, and other large substances, from the sand.

In this trough A, the sand is thoroughly washed, a large quantity of water being supplied to it through the pipe a.

From the trough A, the sand and its impurities flow through the spout e, upon the screen-bottom chute D, which allows all the particles of matter, of a given degree of fineness, and also the water, to fall into the trough E, while the coarser particles of matter flow off the lower end of this chute.

The conveyer F carries the sand along the bottom of the trough E, toward the tube G, and subjects the sand to the action of an opposing current of water, flowing from the spout g toward the chute D, and also to the action of a current of water, flowing from said chute D with the sand.

The two currents of water will meet at or near the spout g', and flow off, carrying with them the particles of matter which are lighter than the sand.

The sand is carried along horizontally through the trough E, and forced through the tube G into a chamber, e; and when this chamber becomes full, and the sand begins to flow over the inclined plane e', the resistance with which the sand in the tubes G meets, in consequence of the body of sand in the chamber e, will cause the conveyer to pack the sand in the tube, and thus compress a large portion of the water out of it.

By this means, I avoid all the objections attending machinery hitherto employed for washing and purifying sand, in which elevators are used. I do not elevate the sand, but carry it through the entire process of washing in horizontal planes, and then deliver it, nearly free from water, where it can be conveniently carried off for use.

Having described my invention,

What I claim as new, and desire to secure by Letters Patent, is—

1. The horizontally-arranged washing-trough A, provided with a screen, O, and a washing-device, in

combination with the horizontally-arranged trough E, provided with a conveyer, F, and a screen-bottom chute, D, substantially as described.

2. The arrangement of the influx-spout g, and the efflux-spout g', in combination with the horizontal trough E, a conveyer, F, and a screen-bottom chute, D, substantially as described.

3. The tube G, or its equivalent, applied to the conveyer F, arranged horizontally, and combined with a sand-washing machine, substantially as described.

4. The receiving-chamber e, in combination with a tube, G, or its equivalent, a trough, E, and a conveyer, F, substantially as described.

5. The inclined plane e', over which the sand is discharged from the trough E, having its highest point above the axis of the conveyer F, substantially as described.

EDWIN BENNETT.
